UNITED STATES PATENT OFFICE

THEODORE A. FEDERWITZ, OF PHILADELPHIA, PENNSYLVANIA, ASSIGNOR TO STOKES AND SMITH COMPANY, OF PHILADELPHIA, PENNSYLVANIA, A CORPORATION OF PENNSYLVANIA

SHEET FEEDER AND CONVEYER

Application filed January 28, 1925. Serial No. 5,225.

My invention relates to apparatus for feeding and conveying sheets, as paper or other material, utilized for any suitable purpose, as, for example, covers or wrappers for boxes, 5 to which there is generally applied an adhesive before application to the boxes.

In accordance with my invention, the driving means for the conveyer, such as a belt or band, is carried upon a support which is capable of movement, preferably pivotal, to and 10 away from operative position with respect to sheet-feeding mechanism, such, for example, as is utilized for feeding sheets to adhesive- or coating-applying mechanism.

Further in accordance with my invention, 15 there is carried upon the aforesaid support for the conveyer-driving means guide plate structure of the sheet-feeding mechanism.

Further in accordance with my invention, 20 there is carried by the aforesaid movable support a roller of a pair utilized for feeding the sheets.

Further in accordance with my invention, 25 there is carried by the aforesaid movable support a roller for guiding and feeding a sheet in contacting relation with the coating-distributing surface.

My invention resides in apparatus of the character hereinafter described and claimed. 30 For an illustration of one of the various forms my invention may take, reference is to be had to the accompanying drawings, in which:

Fig. 1 is a side elevational view, partly in 35 vertical section, of structure embodying my invention.

Fig. 2 is a view similar to Fig. 1, with the movable support thrown back.

Fig. 3 is an end elevational view, partly 40 in vertical section, on the line 3—3 of Fig. 1.

Referring to the drawings, upon the main frame or support 1 of the machine is mounted the driven feed roller 2, with which co-acts 45 the idler feed roller 3 movable toward and away from the roller 2 by mechanism not shown. Supported on the frame 1 is the driven feed roller 4 and the guide plate structure 5, together with the coating roller 6 to 50 which the coating material, as glue, is de-

livered by the roller 7 immersed in the coating material held in the receptacle 8.

Pivoted to the frame 1 upon the studs 9 are the support or frame members 10 united by the bar 11, the latter serving as a handle 55 for moving the frame 10 about its pivots 9 from the operative position indicated in Fig. 1 to the throw-back or inoperative position indicated in Fig. 2 for effecting accessibility to the feeding mechanism.

Carried by the movable support or frame 10 is the roller 12 driven by the forked clutch member 13, between whose ends is received the tongue 14 upon the shaft of the roller 12 and the driving pin 15 secured to the rotating sleeve member 16 driven by the pinion 17 through the longitudinally movable clutch member 18. Threaded into the sleeve member 16 is the sleeve 19, upon which is secured 60 the hand wheel 20 and through which extends the extension 21 on the clutch member 13. Upon rotation of the hand wheel 20 the clutch member 13 is withdrawn toward the left, disengaging the shaft of the roller 12 from its driving means. The member 13 when in the driving position indicated in 65 Fig. 3 serves, in addition to driving the roller 12, to lock the frame 10 against pivotal movement with respect to the main support or frame 1.

Upon the shaft of the roller 12 is a gear 22 driving the gear 23 secured upon the shaft of the co-operating roller 24, which with the roller 12 drives the conveyer band or belt 25, which passes between the rollers 12 and 24 and over the idler roller 26 carried upon the frame 10.

Carried upon the frame 10 is the guide plate structure 27, which co-acts with the guide plate structure 5 to form a guide passage between which the sheets are fed by the feed rollers 2, 3 and 4, 28, the latter carried upon the frame 10.

Carried by the frame 10 is the driven guide or feed roller 29, upon whose shaft is a gear, not shown, which, when the parts are in the position shown in Fig. 1, meshes with and is driven by a driving gear carried by the frame 1.

The operation is as follows:

A sheet is fed by the rollers 2 and 3 between the guide plate structures 5 and 27 to the feed rollers 4 and 28, which further advance the sheet between the guide plate structures 5 and 27 to and between the rollers 6 and 29; the sheet receives coating from the roller 6 while in contact therewith, and is thereafter deflected from the roller 6 by the stripper plates 30 around the idler roller 26 on to the upper side of the conveyer belt 25, which carries it off from left toward the right, Fig. 1.

In the operation described, it frequently occurs that a sheet becomes crumpled or otherwise deformed, or becomes jammed or clogged within that portion of its travel from the feed rolls 2 and 3 to and beyond the co-acting rollers 6 and 29. To remove the obstructions and damaged sheet, the operator first actuates the hand wheel 20, disconnecting the shaft of the feed roll 12 and unlocking the frame 10 from the main frame 1, and thereafter rotates the bar 11 in clockwise direction, as viewed in Fig. 1, rotating in the same direction about the pivots 9 the rolls 12, 24, 26, 28, 29 and the guide plate structure 27, to position indicated in Fig. 2, from which it is apparent that there is ready access to the region above the guide plate structure 5 and adjacent the rolls 2, 3, 4 and 6.

Upon removal of the obstruction, the frame 10 is restored to the position indicated in Fig. 1, the hand wheel 20 operated in reverse direction to effect coupling of the shaft of the roller 12 to its driving means and to lock the frame 10 to the main frame 1.

What I claim is:

1. The combination with a coating-applying machine comprising a roll for applying a coating to a sheet, a sheet-engaging roll between which and said first named roll a sheet is fed, and a guide member for directing a sheet between said rolls, a second guide member spaced from said guide member, of a movable support for said second named roll and second named guide member for moving them to position permitting access between said rolls and guide members.

2. The combination with a coating-applying machine comprising a roll for applying a coating to a sheet, a sheet-engaging roll, and rolls coating to feed a sheet to be engaged by said coating-applying and sheet-engaging rolls, of a movable support carrying said sheet-engaging roll and one of said coating sheet-feeding rolls for removing the sheet-engaging roll to position permitting access between said first-mentioned roll and said sheet-engaging roll and between said sheet-feeding rolls.

3. The combination with a coating-applying machine comprising a roll for applying a coating to a sheet, a sheet-engaging

roll between which and said first-named roll a sheet is fed, a guide member for directing a sheet between said rolls, a second guide member spaced from said guide member, and co-acting sheet-feeding rolls, of a movable support carrying one of said co-acting sheet-feeding rolls, said sheet-engaging roll and said second-named guide member for moving said sheet-engaging roll and said second-named guide member to position permitting access between said first-mentioned roll, said sheet-engaging roll and said guide members.

4. The combination with a coating-applying machine comprising a roll for applying coating to a sheet, a second roll disposed adjacent thereto, an endless conveyer band traveling over said second roll to receive and transport sheets after application of adhesive thereto, and means for driving said band, of a movable support carrying said second roll and said band-driving means for moving them to position permitting access between said rolls.

5. The combination with a coating-applying machine comprising a roll for applying coating to a sheet, a second roll disposed adjacent thereto, a conveyer band traveling over said second roll, means for driving said band, and a third roll between which and said coating-applying roll a sheet passes, of a movable support carrying said second and third rolls and said band-driving means to effect movement of said rolls to position permitting access between them and said first named roll.

6. The combination with a coating-applying machine comprising a roll for applying coating to a sheet, a second roll disposed adjacent thereto, a conveyer band traveling over said second roll, means for driving said band, a third roll between which and said coating-applying roll a sheet passes, a guide member directing a sheet between said third roll and said coating-applying roll, and a co-acting guide member spaced from said guide member, of a support carrying said second and third rolls, said second named guide member and said band-driving means for effecting movement of said rolls and guide member to position to permit access between them and said coating-applying roll and said first named guide member.

7. The combination with a coating-applying machine comprising a coating-applying roll, a conveyer band, means for feeding sheets to said roll and band, and means for driving said band, of a movable support carrying said driving means, and means for holding said support in predetermined position and for driving said band-driving means.

8. The combination with a coating-applying machine comprising a coating-applying roll, a conveyer band, means for feeding sheets to said roll and band, and a roll for driving said band, of a movable support car-

rying said second named roll, and a member through which said second named roll is driven for locking said movable support in operative position.

means for pivoting said support to permit access between said feed rolls.

5 9. The combination with a coating-apply-
ing machine comprising a coating-apply-
ing roll, a conveyer band, means for feeding
sheets to said roll and band, and a roll for
driving said band, of a pivoted manually
10 operable support carrying said second named
roll, and a member co-axial with said second
named roll through which it is driven and
serving when in roll-driving position to lock
said support in operative position.

15. The combination with a coating-applying machine comprising a roll for applying coatings to sheets, of co-acting feed rolls for feeding sheets in succession toward said roll, sheet-guiding members spaced from each other, a conveyer band, a roll over which said band travels, a support carrying one of said feed rolls, one of said guide members and said last named roll, and means for pivoting said support to permit access between said feed rolls and guide members. 70 75

15 10. The combination with a coating-applying
ing machine comprising a coating-applying
roll, a conveyer band, means for feeding
sheets to said roll and band, a roll for driving
said band, and a fixed frame member, of a
20 manually operable support pivoted on said
frame member and carrying said second
named roll, and a member carried by said
frame member co-axial with said second
named roll and movable axially thereof to
25 position for driving said roll and for hold-
ing said pivoted support in fixed position
with respect to said frame member.

16. The combination with a coating-apply-
ing machine comprising a roll for applying
coatings to sheets, of co-acting feed rolls for
feeding sheets in succession toward said
first named roll, a conveyer band, a roll
over which said band travels, a support
carrying one of said feed rolls and said
last named roll, means for pivoting said sup-
port to permit access between said feed rolls,
and means for driving said band carried by
said support. 85

11. The combination with a coating-applying machine comprising a roll for applying coatings to sheets, of co-acting feed rolls for feeding sheets in succession toward first said roll, guide members spaced from each other, and a movable support for one of said rolls and one of said guide members for removing them from their operative positions to effect access to the other roll and guide member.

17. The combination with a coating-apply-
ing machine comprising a roll for applying
coating to sheets in succession, sheet-guid-
ing members spaced from each other, a con-
veyer band, a roll over which said band
travels, a support carrying one of said feed
rolls, one of said guide members and said
last named roll, means for pivoting said sup-
port to permit access between said feed rolls
and guide members, and means for driving
said band carried by said support. 10

12. The combination with a coating-applying machine comprising a roll for applying coatings to sheets, of co-acting feed rolls for feeding sheets in succession toward said first roll, guide members spaced from each other, a support for one of said rolls and one of said guide members, and means for pivoting said support to permit access between said rolls and guide members.

18. The combination with a coating-applying machine comprising a roll for applying coatings to sheets in succession, sheet-guiding members spaced from each other, a conveyer band, a roll over which said band travels, a support carrying one of said feed rolls, one of said guide members and said last named roll, means for pivoting said support to permit access between said feed rolls and guide members, and co-acting band-driving rolls carried by said support. 105 110

13. The combination with a coating-applying machine comprising a roll for applying a coating to a sheet, a sheet-engaging roll between which and said first named roll a sheet is fed, a guide member for directing a sheet between said rolls, and a second guide member spaced from said first named guide member, of a support for said second named roll and said second named guide member, and means for pivoting said support to permit access between said rolls and guide members.

by said support.

63 14. The combination with a coating-apply-
64 ing machine comprising a roll for applying coat-
65 ings to sheets, co-acting feed rolls for feed-
66 ing sheets in succession toward said first
67 named roll, a conveyer band, a roll over which
68 said band travels, a support carrying one of
69 said feed rolls and said last named roll, and
